US0D1097741S

(12) **United States Design Patent** (10) **Patent No.:** **US D1,097,741 S**
(45) **Date of Patent:** **** Oct. 14, 2025**

(54) **PICK**

(71) Applicant: **Milwaukee Electric Tool Corporation**,
Brookfield, WI (US)

(72) Inventors: **Hunter M. Schwei**, Milwaukee, WI
(US); **Jack R. Warning**, Sussex, WI
(US)

(73) Assignee: **Milwaukee Electric Tool Corporation**,
Brookfield, WI (US)

(**) Term: **15 Years**

(21) Appl. No.: **29/922,292**

(22) Filed: **Dec. 21, 2023**

Related U.S. Application Data

(62) Division of application No. 29/793,029, filed on Jan.
10, 2022, now Pat. No. Des. 1,015,095.

(74) *Attorney, Agent, or Firm* — Reinhart Boerner Van
Deuren s.c.

(57) **CLAIM**

The ornamental design for a pick as shown and described.

DESCRIPTION

FIG. 1 is a perspective view of a pick, embodying the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is another perspective view of the pick of FIGS. 1 through 7, illustrated without surface shading;

FIG. 9 is a front elevation view of FIG. 8;

FIG. 10 is a rear elevation view of FIG. 8;

FIG. 11 is a left-side elevation view of FIG. 8;

FIG. 12 is a right-side elevation view of FIG. 8;

FIG. 13 is a top plan view of FIG. 8; and,

FIG. 14 is a bottom plan view of FIG. 8.

The ornamental design which is claimed is shown in solid lines in the drawings. The broken lines in the drawings are for illustrative purposes only and form no part of the claimed design. The broken dot-dash lines define boundaries of the claimed design and form no part thereof.

1 Claim, 8 Drawing Sheets
